[57] CLAIM

The ornamental design for a vacuum operated insect collector, substantially as shown.

DESCRIPTION

FIG. 1 is a front elevational view of a vacuum operated insect collector showing my new design;
FIG. 2 is a top plan view thereof;
FIG. 3 is a left side elevational view thereof;
FIG. 4 is a right side elevational view thereof; and
FIG. 5 is a bottom plan view thereof.

FIG. 2

FIG. 1
